UNITED STATES PATENT OFFICE.

ALBERT E. MILLER, OF GENESEO, ILLINOIS.

FODDER-RACK.

1,242,361.

Specification of Letters Patent.

Patented Oct. 9, 1917.

Application filed March 24, 1917. Serial No. 157,199.

To all whom it may concern:

Be it known that I, ALBERT E. MILLER, a citizen of the United States, residing at Geneseo, in the county of Henry and State 5 of Illinois, have invented certain new and useful Improvements in Fodder-Racks, of which the following is a specification.

This invention relates to racks for holding fodder of various sorts, and more particularly for holding green corn fodder.

One of the main objects of the invention is to provide a rack of the character stated of simple and durable construction which can be quickly and easily applied to a wagon 15 base of standard construction. A further object is to provide a rack which can be easily removed from or mounted upon a wagon base without the necessity of disassembling the rack in any way. A still further object is to provide a rack the various 20 elements of which are secured together by clamping thus avoiding weakening of the rack frame due to the insertion of securing nails or similar devices through the same. 25 Further objects will appear from the detail description.

In the drawings:—

Figure 1 is a side view of a rack constructed in accordance with my invention 30 as used,

Fig. 2 is a top plan view of the rack,

Fig. 3 is a section on line 3—3 of Fig. 1,

Fig. 4 is a section on line 4—4 of Fig. 1,

Fig. 5 is a detail of the construction of 35 the end portion of the rack.

The body of the rack is composed of four parallel beams 1, 2, 3, and 4, mounted in parallel spaced relation, and all of the same length. The beams are held against spreading 40 by clamps composed of an upper cross piece 6 and a lower cross piece 7 mounted above and beneath the beams, respectively, these cross pieces extending laterally of the outer beams and being secured tightly together by suitably spaced bolts 8 and nuts 9 threaded thereon. The beams, together 45 with the clamps constitute the body of the rack frame. Mounted between the beams are suitable boards or planks 10, each board 50 corresponding in length to the beams 5, and in width to the distance apart of the beams. The boards 10 constitute a flooring for the frame and also serve as spacing members to hold the beams in proper spaced relation 55 preventing inward movement of the outer beams intermediate the end pieces and hold-

ing the inner beams 2 and 3 in proper spaced relation to each other and to the outer beam. adjacent the front end of the outer beam 1 an upwardly extending arm 11 is secured 60 thereto by a bolt 12, a similar arm 13 being secured to the outer beam 4 in alinement transversely of the rack frame with arm 11. These two arms are secured together at their upper ends by a cross piece 14, the two arms 65 and the cross piece coöperating to form a retaining standard. Arms 15 and 16 are similarly secured to each of the outer beams adjacent the back thereof so as to constitute a rear retaining rack. Each of these racks 70 is held in an upwardly directed slightly inclined position by a clamp secured about the beams closely adjacent the rack arms.

A bolster 17 is secured to the underside of the rack frame a short distance from the 75 front of the same. This bolster is centrally apertured to receive a king bolt 18 which is inserted through the pillow block 19 carrying the front axle 20 on which are mounted the ground wheels 21 and 22. A bolster 80 23 is secured to the underneath of the rack frame remote from the back of the same and may be formed from a piece of two by six inch timber. This bolster is secured by clips 24 to the rear pillow block 25 carrying the 85 rear axle 26 on which are mounted the ground wheels 27 and 28. The clips 24 are of standard construction being passed about the bolster and pillow block and secured in position by plates 27^a extending beneath 90 the axle 26 and held in position by nuts 28^b threaded on the ends of the clip. The bolster 23 is secured to the outer beams 1 and 4 of the frame by means of clips 29 and 30, respectively, placed over these beams and the 95 bolster, similar to clips 24. By this means the rack is secured on the wagon base so as to be supported thereby and may be quickly and easily removed by the simple expedient of removing the king bolt 18 and the securing clips 29 and 30, after which the rack may be lifted as a unit from the wagon base.

To permit short turns to be made, a steel arch 33 is interposed in the outer beam 1. This arch is curved upward and so positioned as to permit the front ground wheel 21 to turn under the same, the arch being provided at each end with an integral socket of rectangular cross section which fits snugly about the end of the spaced portion of the 110 beam and is secured thereto by means of bolts passed through the socket and the

beam, the bolts for the front socket being passed through pillow block 17 so as to secure the same to the frame. A similar arch 34 is interposed in the outer beam 4 to accommodate the ground wheel 22. These arches also act as guards to prevent the material placed on the rack from contacting with the front ground wheels. Rear wheel guards 35 and 36 are secured to the outer beams so as to extend above the rear ground wheels for a similar purpose.

A rack constructed in this manner is very strong and well adapted to support unusually heavy loads. In addition, the beams 15 of the frame which extend above the flooring serve as projections for gripping the material of the load so as to prevent slippage of the same. This is especially true when the rack is used for holding green corn fodder 20 which may be loaded with the stalks extending transversely of the frame, the edges of the beams serving to grip the fodder stalks and thus materially assist in maintaining the load in proper position upon the vehicle. As this rack sits very low it is especially adapted for hauling green corn fodder 25 to shredders for shredding and loading the same into silos. The fodder can be quickly and easily loaded onto the racks, and easily 30 removed, this work being done by one person instead of two being required as is the case where high racks are used. In addition, the rack may be quickly and easily applied to the base of any farm wagon of standard 35 construction. This rack is also well adapted for hauling hay, sacked grain, and various other materials. It is also to be noted that a rack constructed in this manner is entirely free from all nails and similar securing ele-

ments which are apt to become rusted and, 40 being inserted through the material of the rack frame, to weaken the rack.

What I claim is:

1. In fodder racks, a plurality of beams 45 mounted in spaced parallel relation, transverse clamps mounted about said beams and extending above and beneath the same, and boards interposed between the beams and supported by said clamps, the clamps and boards coöperating to hold the beams in 50 parallel spaced relation.

2. In fodder racks, a plurality of beams mounted in parallel spaced relation, transverse clamps secured about said beams and 55 extending above and beneath the same, and boards mounted between the beams, said boards corresponding in length and width to the spaces between the beams and coöperating with said clamps to maintain all of 60 said beams in proper spaced relation.

3. In fodder racks, a plurality of beams mounted in parallel spaced relation, pairs of transversely extended strips positioned above and beneath the beams, and constituting 65 clamping members for securing the said beams, means for forcing the strips of each pair toward each other and for preventing outward lateral movement of the outer-most of said beams, and boards supported by the 70 lower strips of said pairs of strips interposed between the beams so as to maintain the same in spaced relation.

In testimony whereof I affix my signature in presence of two witnesses.

ALBERT E. MILLER.
